UNITED STATES PATENT OFFICE.

ELBRIDGE G. HOWE, OF MILLBURY, MASSACHUSETTS.

BOTTLE-STOPPER.

SPECIFICATION forming part of Letters Patent No. 749,063, dated January 5, 1904.

Application filed December 6, 1902. Serial No. 134,075. (No model.)

To all whom it may concern:

Be it known that I, ELBRIDGE G. HOWE, a citizen of the United States, residing at Millbury, in the county of Worcester and Commonwealth of Massachusetts, have invented a new and useful Improvement in Bottle-Stoppers, of which the following is a specification, accompanied by drawings forming a part of the same, in which—

Figure 1 is a perspective view of the neck of a bottle with a glass stopper and a metallic retaining-cap applied thereto embodying my invention. Fig. 2 is a perspective view of the mouth of a bottle with its glass stopper, 15 the metallic retaining-cap having been removed. Fig. 3 is a perspective view of the neck of a bottle with the glass stopper and metallic cap removed and showing the annular ground surface around the mouth of the 20 bottle. Fig. 4 is a perspective view of the glass stopper inverted, showing its under side; and Fig. 5 is a central vertical sectional view representing the neck of a bottle with its glass stopper and metallic cap applied thereto. 25 Similar reference-figures refer to similar parts in the different views.

The object of my present invention is to provide a hermetically-sealed glass bottle or similar vessel without the employment of 30 other material for the purpose of rendering the joint of the stopper air-tight, thereby enabling the contents of the vessel to be preserved hermetically sealed under absolute sanitary conditions; and my invention consists in the construction and arrangement of 35 parts, as hereinafter described, and set forth in the annexed claims.

Referring to the accompanying drawings, 1 denotes the upper portion or neck of a glass 40 bottle provided with a glass stopper 2 and a metallic retaining-cap 3, by which the stopper is retained in position. The stopper 2, which is shown in inverted perspective view in Fig. 4, consists of a circular glass disk having on 45 its under side a rib 4 with a flat surface 5 and having its upper side slightly conical, as at 6, and provided with a series of notches or radial slots 7. The neck of the bottle is of sufficient thickness to provide a flat surface 50 8 around the mouth of the bottle and lying in a plane substantially at right angles with the axis of the bottle. The flat surfaces 5

and 8 on the stopper and bottle are ground, preferably by placing the flat surfaces 5 and 8 in contact with some intervening abrading material, such as flour of emery, and rotating the cap on the bottle with a slightly eccentric motion, so that both surfaces 5 and 8 are simultaneously ground to form an air-tight joint, the radial notches or slots 7 in the upper surface of the cap furnishing the means for the engagement of the cap with the rotating mechanism. The rib 4 limits the area to be ground to an annular surface corresponding substantially with the annular surface 8 on the bottle and leaving the cap when applied to the bottle free to slide laterally in any direction, but forming an air-tight joint between the ground surfaces 5 and 8 without the employment of a gasket or other compressible packing material.

The stopper 2 when applied to the bottle is held in place by means of a metallic retaining-cap 3, which consists of a ring provided with an internal screw-thread adapted to engage a screw-thread 9, formed on the outside of the neck of the bottle and having its top 10 overlapping the edge of the glass stopper 2. The retaining-cap 3 is provided with a central hole 11, which receives the apex of the 80 conical surface 6. The metallic cap 3 is provided on its periphery with a series of spurs 12, adapted to be engaged by a spanner, whereby the cap is rotated and drawn down by the screw-thread 9, thereby pressing the edge 13 85 of the cap against the conical surface 6 of the stopper. The hole 11 in the metallic cap, in connection with the conical surface on the stopper, serves to center the stopper on the neck of the bottle, and by applying the pressure of the retaining-cap 3 at the edge 13 I 90 obtain a yielding pressure against the cap, which allows the cap to be rotated slightly after the edge 13 has been brought into contact with the conical surface of the stopper, 95 and as the yielding pressure of the cap against the stopper is received by the screw-thread 9 on the neck of the bottle the cap is frictionally held against accidental displacement. The removal of the metallic retaining-cap releases the glass stopper, which can be readily pushed to one side and removed from the 100 bottle.

It has been customary heretofore to apply

glass stoppers or covers to the mouths of jars, said stoppers being held from displacement by engaging a shoulder or rib on the neck of the jar. This construction prevents the grinding of the glass surfaces in contact and requires a rubber gasket or compressible packing-ring to render the joint air-tight. Glass stoppers which have heretofore been ground and adapted to be inserted in the neck of a bottle, which is also ground, have the disadvantage of becoming wedged in place and removed with difficulty.

What I claim as my invention, and desire to secure by Letters Patent, is—

- 15 1. The combination with a vessel having an annular ground surface surrounding its mouth, of a glass stopper, consisting of a circular disk having on its under side a projecting annular rib corresponding to the annular ground surface on said vessel and provided with a ground surface, substantially as described.
- 20 2. The combination of a vessel and a cover seated upon the mouth of the vessel and having a conical projection on its upper surface, and a retaining-cap having a central hole to receive said conical surface and means for attaching said cap to the vessel, substantially as described.
- 25 3. The combination with a vessel having an annular ground surface surrounding its mouth, of a glass stopper consisting of a disk

provided with an annular projecting rib on its under side having a ground surface corresponding to the annular ground surface of 35 said vessel and means for retaining said disk on the vessel, with their ground surfaces in contact, substantially as described.

4. The combination with a glass vessel having an annular ground surface around its 40 mouth lying in a plane substantially at right angles with the axis of the vessel, a glass cap having a rib with a ground face corresponding with the ground surface on the vessel and having a conical upper surface, a metallic cap 45 inclosing said stopper and means for engaging said cap and the vessel, substantially as described.

5. The combination with a glass vessel, of a glass stopper, said stopper and vessel having 50 plane contacting ground surfaces lying substantially in a plane at right angles with the axis of the vessel, said stopper having a conical top, a metallic cap overlapping said stopper and having a central hole to receive the 55 conical top of the stopper and means for drawing said cap against the stopper, substantially as described.

Dated this 1st day of December, 1902.

ELBRIDGE G. HOWE.
